UNITED STATES PATENT OFFICE.

LUDWIG FRANZ, OF MUNICH, GERMANY, ASSIGNOR TO THE FIRM C. A. STEINHEIL SÖHNE, OF MUNICH, BAVARIA, GERMANY.

ADAPTATION OF SIGHTING TELESCOPES FOR NOCTURNAL USE.

Application filed June 25, 1921. Serial No. 480,389.

(GRANTED UNDER THE PROVISIONS OF THE ACT OF MARCH 3, 1921, 41 STAT. L., 1813.)

To all whom it may concern:

Be it known that I, LUDWIG FRANZ, a citizen of the Republic of Germany, residing at Munich, Bavaria, Germany, have invented certain new and useful Improvements Relating to the Adaptation of Sighting Telescopes for Nocturnal Use, of which the following is a specification, and for which I have made application in Germany filed June 28, 1918, under No. St. 31297IX/42h.

Aiming telescopes for fire-arms have long been generally known; they are intended to secure accurate firing in daylight or possibly in twilight. For hunting at night or in the dusk night aiming devices as described in my patent application No. 480,390, filed June 25, 1921, are best adapted; they require therefore no further description here. Both of these devices can be used with one and the same fire-arm; this was made possible heretofore by making those parts of the aiming telescope and of the night aiming device, which served to connect the same to the gun, exactly similar in both devices. Such an arrangement has however the great disadvantage, that two separate devices are necessary, which is both inconvenient and expensive. The present invention unites both devices in one and the same apparatus. The general idea of the invention is as follows:

In the image-plane of the objective of an aiming telescope a dark aiming-mark is so arranged, that it shows the striking point of the bullet in an image of the object aimed at, said image being projected by the objective. To convert an aiming telescope into a night aiming device, the image of the incandescent cross-line of the night aiming device must obviously be arranged to occupy the exact position of the aiming mark of the aiming telescope, since the point of intersection of the cross-line also coincides with the striking point of the bullet. The aiming mark of the aiming telescope will however then totally or partly intercept the light coming from the incandescent cross-line, especially the light from that part of the cross-line which is indispensable for the purpose of aiming. This necessitates the removal of the aiming mark out of the

image-plane when converting the aiming telescope into a night aiming device. The present invention refers to means by which this result can be attained.

The aiming mark of an aiming telescope is measurably movable for adjusting it to different ranges. This delicate adjusting and measuring device may not be interfered with by the removal of the aiming mark and this indispensable requirement constitutes the chief difficulty in converting an aiming telescope into a night-aiming device. The means employed to secure this conversion can be different, according to the type of the aiming telescope in question; but they all have the same end in view, namely to avoid a disturbance of the accuracy of the aiming-telescope through the conversion.

The aiming telescope with lens reversing system has two image-planes, namely the front-image plane of the objective and the rear image-plane of the eye-piece. Since the aiming mark of the aiming telescope is arranged in the front image-plane, the lamp can be placed in the rear plane, a mirror being at the same time substituted for the eye-piece, thus converting the aiming telescope into the best and most usual type of night aiming device. The aiming mark of the aiming telescope, however, here obstructs the rays coming from the incandescent cross-line, since the image of the latter is projected by the reversing system directly onto said aiming mark, being thereby partly extinguished. In this case the present invention removes the obstruction by shifting the aiming mark (generally in a downward direction) in the image plane itself so far out of the path of the rays coming from the incandescent cross-line, that the latter can pass without hindrance. This shifting of the aiming mark can conveniently be attained with the help of the adjusting and measuring device of the aiming telescope, which, being generally known, need not here be described in detail. However it is in this case necessary that the aiming mark contains no parts parallel to the direction of adjustment of the aiming mark, or at least no parts on the side opposite to the direction of movements (as a

rule therefore on the upper side). In the case of this conversion it is further necessary to make the diaphragm in the image plane of the objective larger than the field of view of the aiming telescope, as otherwise the beam of diffused light of the night aiming device would be obstructed. The field of view must therefore be limited by a diaphragm in the image-plane of the eye-piece, said diaphragm being removable with the eye-piece, since it lies directly in the plane of the lamp.

Aiming telescopes with a prism reversing system possess only one image-plane. In this case therefore, the aiming mark must be removed from the image-plane of the objective so far apart in the direction of the optical axis, that there is room for the lamp and that at the same time the aiming mark will not perceptibly obstruct the light rays of the night aiming device.

The present invention provides two means to gain this result, namely:

1. The mechanical removal of the aiming mark out of the image plane;
2. The optical displacement of the image-plane out of the plane of the aiming mark.

Referring to means 1:

In contradistinction to the usual rigid connection of the measuring and adjusting device with the aiming mark, the present invention in this case makes the aiming mark removable from the adjusting device. The simplest and most reliable means is the shifting of the aiming mark in the direction of the optical axis in order to make room for the lamp. The measuring and adjusting device can also be designed to be bodily removed and its place taken by the lamp. It is obvious, that these mechanical interchanges can also be applied to night aiming devices with a lens reversing system.

Referring to means 2: The present invention in this case introduces a positive or negative lens, by the displacement of which in an axial direction the image-plane of the objective is removed so far from the plane of the aiming mark, that the effect of the latter on the rays of the night aiming device is negligible. Here also it is necessary to make the diaphragm for the field of view removable with the eye-piece.

The accompanying drawings represent the present invention in several different adaptations together with details. To avoid unnecessary complications the drawings are diagrammatic and show only those parts which are essential to the present invention.

Fig. 1 shows the optical parts and the ray paths of an aiming telescope with lens reversing the system, in which the planes *c* and *d* at right angles to the optical axis, represent the two image planes of the aiming telescope. Fig. 2 shows this telescope

converted into a night aiming device; the lamp 1 has been introduced into the image plane *d* and the eye-piece 5 exchanged for a concave mirror 3. Figs. 3 and 4 show types of aiming marks for use here with the aiming telescopes; the image 10 of the incandescent cross-line of the projector lamp of the night aiming device is here indicated by dotted lines. In Fig. 5 an aiming telescope with a prism or mirror reversing system is shown, in which a negative lens 6 has been arranged in close proximity to the image-plane *c*. Fig. 6 shows this telescope converted into a night aiming device; by shifting the lens 6 the image-plane has been displaced. Figs. 7 and 8 show similar devices to Figs. 5 and 6, but instead of a negative lens a positive lens 13 has here been introduced.

The following denominations are common to all the figures: 1 is the electric lamp of the night aiming device; 2 an objective, which in the case of an aiming telescope projects an image of the object aimed at in the plane of the aiming mark, whereas in the case of a night aiming device it projects the incandescent cross-line of the lamp onto the object aimed at; 3 is the concave mirror of the night aiming device adapted to create a beam of diffused light; *c* is the image-plane of the aiming-mark, at right angles to an optical axis; *d* is the image-plane of the lamp of the night-aiming device, also at right angles to the optical axis.

In the following the several figures will be described in detail. The principle of the aiming telescope is generally known and needs no further description; the night aiming device is described in my patent application No. 480,390, filed June 25, 1921, to which I hereby refer.

According to Fig. 1 the objective 2 produces an inverted image of the object aimed at in the image-plane *c*, in which an aiming mark similar to Fig. 3 or 4 is arranged. The lens reversing system 4 then projects this image upright together with the aiming mark in the image-plane *d*, in which both can be simultaneously viewed through the astronomical eye-piece 5. A diaphragm 7 is rigidly connected with the eye-piece 5, said diaphragm limiting the field of view of the aiming telescope and being detachable with the eye-piece. In order to convert this aiming telescope into a night aiming device (Fig. 2) the eye-piece 5 is removed and the concave mirror 3 attached in its place; the lamp 1 is then inserted in the image-plane *d*. The reversing system 4 now produces an image of the incandescent cross-line of the lamp in the image-plane *c*, where it will coincide with the position of the aiming mark when the latter is in the position for firing, because this aiming mark is adjusted to cover the same point of the

target as the incandescent cross-line of the lamp. In the case of an aiming-mark of the form 8 (Fig. 3) only the horizontal thread is extinguished, whilst in the case of 5 an aiming mark of the form 9 (Fig. 4) also half of the vertical thread will be extinguished. Both forms are already known; but their use is absolutely essential to the present invention. The necessary displacement 10 of the aiming mark is attained by moving said mark downwards in the image-plane *c* itself which can be most conveniently accomplished by means of the device already provided for adjusting the aiming mark 15 when in use as part of the aiming telescope; it may perhaps be necessary to give this adjusting device a somewhat greater range of movement downwards. The aiming mark according to 8 (Fig. 3) is to be given the 20 preference, as here only a very small part of the vertical thread is darkened, whilst in the case of an aiming mark according to 9 (Fig. 4) the whole of the lower half of the vertical thread disappears.

25 The position of the incandescent cross-line 10 when using the instrument as a night aiming device is indicated by dotted lines in Figs. 3 and 4. Figs. 1 and 2 are typical of the device according to the present invention.

Fig. 5 shows the optical parts of the well known prism aiming telescope, a negative lens 6 being introduced and arranged quite near to the image-plane *c* of the objective, 35 said negative lens having in this position hardly any effect on the optical rays. The objective 2 projects an image of the object aimed at, which is reversed by the mirror reversing system 11,12, so that it can be viewed 40 together with the aiming mark through the astronomical eye-piece 5. The diaphragm 7 for limiting the field of view must here also be connected to and detachable with the eye-piece 5, because for the night aiming device a larger aperture than 45 said diaphragm is required in the plane *c*. In order to adapt the device for use as a night aiming device the negative lens 6 is shifted from *c* to *i*, thereby displacing the image-plane from *c* to *d* and at the same time increasing the focal distance of the 50 objective. The lamp 1 can now be inserted in the image-plane *d* and at the same time the eye-piece 5 exchanged for the mirror 3. The aiming mark, for instance Fig. 3, being 55 at a considerable distance from the image-plane, will now hardly prove an obstruction and can also, if necessary, be shifted down-

wards. Figs. 7 and 8 represent the same device as Figs. 5 and 6, the reversal of the 60 image being however here produced by a positive lens 13; when the device is in use as an aiming telescope, this positive lens 13 must of course be in the plane *i*, thereby 65 reducing the focal distance of the objective 2; to adapt the device for use as a night aiming device said positive lens 13 is shifted to *c* where it will exert less influence on the ray paths; the image-plane is hereby displaced from *c* to *d* and the focal distance 70 of the apparatus increased. In all other respects this form of the device is similar to Figs. 5 and 6.

What I claim as my invention and desire 75 to secure by Letters Patent is:

1. The herein described method of converting an aiming telescope with an aiming mark in the image plane of the objective into a night aiming device, which consists in introducing a lamp of a night aiming 80 device into the image plane of an eye piece of the telescope, and arranging a concave mirror of a night aiming device in place of said eye piece.

2. The herein described method of converting an aiming telescope with an aiming mark in the image plane of the objective into a night aiming device, which consists in making a beam of light issuing from a lamp disposed in the image plane of an eye 90 piece reflect in a concave mirror arranged in the plane of said eye piece, and producing an image of an incandescent cross line of 95 said lamp in an image plane disposed in advance of said lamp by means of a reversing system disposed between the lamp and said last named image plane.

3. The arrangement of elements in an aiming telescope to produce a night aiming device of the character described, which 100 comprises an objective and a lens reversing system, an image plane disposed between said objective and reversing system, a concave mirror arranged in the place of an eye 105 piece in said telescope, and a lamp having an incandescent cross-line which produces an image in said image plane, said lamp being arranged in the image plane of said eye piece if the latter were present.

In testimony whereof I hercunto affix my 110 signature in the presence of two witnesses.

LUDWIG FRANZ.
